CAN MAKING MACHINE

Frank Krueger, Brooklyn, N. Y., assignor to E. W. Bliss Company, Brooklyn, N. Y., a corporation of Delaware

Application June 29, 1939, Serial No. 281,910

7 Claims. (Cl. 113—7)

This invention relates to can body making machines and is particularly adapted to machines in which the blanks are flexed before they are fed into the body maker.

The sheet material, usually tin plate from which can bodies are made, possesses a resiliency and resistance to bending which should preferably be removed before the ends of the can are placed on the body. For this reason a body maker normally includes a flexing station where the sheet is sharply bent to break the grain and remove its resiliency. This has heretofore been a separate operation, and was effected either before or after the blank was made into a can body.

In modern high speed can machinery, it is desirable to operate the body maker as fast as possible and to provide flexed sheets to be fed into the body maker in sufficient quantity to provide a continuous supply. This should be accomplished without the necessity of a workman constantly replenishing the magazine from which the blanks are fed to the body maker.

Furthermore, such flexing mechanism should operate at a sufficiently high speed to flex blanks more rapidly than they are used by the body maker to thus insure a continuous supply of flexed blanks to the body maker.

The general object of my invention therefore has been to provide a unit to be placed ahead of the body forming mechanism to automatically supply properly flexed blanks thereto. Still another object of my invention has been to provide a pair of magazines with a flexing device interposed therebetween in which the blanks are fed from one magazine, hereinafter referred to as the flexing magazine, through the flexing device to a second magazine, hereinafter referred to as the body maker magazine which, in turn, supplies the flexed blanks to the body maker. An additional object of my invention has been to provide a flexing device of improved construction which will operate faster and more efficiently than similar machines heretofore used. Other objects of the invention will become apparent from the following specification when read in the light of the accompanying drawings, and the novel features are summarized in the claims.

As heretofore indicated, a machine in accordance with my invention is employed to flex the blanks before they are fed to the forming machine of the body maker by which they may be notched and edged and formed into shape. The invention generally comprises a first or flexing magazine from which blanks are fed through a flexing device into a second or body making magazine.

The blanks are automatically fed from the second or body making magazine into the body maker. The various mechanisms are so timed and interconnected that blanks are fed faster from the first or flexing magazine into the flexing rolls and thence to the body maker magazine than such blanks are withdrawn from the body maker magazine and passed into the body maker. A control mechanism is associated with the body maker magazine to render the flexing device and its associated parts inactive upon attainment of a predetermined height of flexed blanks in the body maker magazine. As the supply of blanks in the body maker magazine diminishes, the control mechanism permits the flexing device to supply more blanks to the said magazine until the level of the flexed blanks in said magazine is again restored.

In said annexed drawings:

Fig. 1 is a plan view of the apparatus of my invention;

Fig. 2 is a composite diagrammatic section thereof with various portions of the structure cut away, the section being taken substantially along the line 2—2 of Fig. 1;

Fig. 3 is a vertical detail of the flexing device control operated by the height of the stack of flexed blanks in the body maker magazine;

Fig. 4 is an end elevation of the flexing device as viewed from the right in Fig. 2;

Figs. 5, 6, 7, 8, 9 and 10 are fragmentary sections through Fig. 1, as indicated by the corresponding lines thereon; and

Fig. 11 is a fragmentary section through Fig. 2 as indicated by the line 11—11 thereon.

Referring particularly to Fig. 1, my invention is incorporated with a conventional body maker as indicated thereon and not further discussed, since its features are well known in the art.

A body maker magazine, indicated generally at 10, is employed to supply flexed blanks to the body maker and comprises a pair of side plates 12 and 14 and end plates 15 and 16. The size of the body maker magazine is adjustable to allow its use with flexed blanks of different sizes. Blanks are fed one at a time from the bottom of this magazine 10 in the direction of the arrow (Fig. 1) into the notching and edging mechanism and thence to the body maker or former. The feeding of the flexed blanks is accomplished by the feed fingers of a conventional body maker, not shown.

The blank may be first notched at the station indicated at 20 and may be then edged at the station 22, passing from this station into a wing-

form body maker. It will be apparent that different kinds of body makers may be employed with the present invention, the type just described being specified only for convenience of illustration. A bed 25 supports the body maker parts and the body maker magazine 10. Bolted above and to the bed 25 at 27 is a frame 30 which supports the parts of the flexing machine and ties it as a cooperating unit to the parts on the bed 25.

A flexing magazine is carried by the frame 30, from which blanks are withdrawn downwardly and fed to the flexing rolls and then into the body maker magazine 10 through an opening in the side plate 14. This flexing magazine comprises three side wall members 32, 33 and 34. These parts in turn are adjustably bolted in ways 35 on the upper surface of the frame 30, and the member 32 is adjustable transversely of said ways by reason of the slot 37 and a conventional clamping bolt 37'. Each of the side members is provided at the bottom with circular wedge shaped discs 38, which discs are hardened to resist wear and serve to support the stack of blanks in the magazine. The discs are removably retained by bolts 39. It will be apparent that by adjusting the side wall members 32, 33 and 34, the size of the flexing magazine may be varied to accommodate blanks of varying sizes.

A pair of pneumatic suckers below the flexing magazine withdraw one blank at a time from the bottom of the stack of blanks in said magazine. These suckers, indicated at 40, are adjustably bolted at 42 in a transverse slot 43 and a longitudinal slot 44. A frame member 45 is bolted at 47 to the top of a column 48 (see Fig. 2). This column 48 is slidably carried in a boss 48 formed on the frame 30 and is alternately raised and lowered to move the successive, lowermost sheets from the stack in the flexing magazine. A pin 50 carried by the frame member 45, is slidably guided in a boss 52 formed on the frame 30, and cooperates with the column 48 to maintain the member 45 in position.

The suckers 40 and other movable parts of the apparatus of my invention are driven from an electric motor 52 bolted at 54 to the underside of the bed 25. A chain drive 55 from the motor 52 to a gear 57 drives a shaft 60 journaled transversely of the direction of feed of the blanks from the flexing magazine to the flexing rolls. A sucker cam 62 is keyed to the shaft 60 to be rotated therewith, and imparts movement to a rock arm 63 pivoted intermediate its ends at 64 to the machine frame 30. The other end of the rock arm 63 carries a roller 65 engaging with the column 48. Thus, as the motor 52 rotates the shaft 60, the cam 62 raises and lowers the column 48 and moves the suckers 40 into and out of engagement with the lowermost blank of the stack in the flexing magazine.

A vacuum is created at the suckers 40 as they are reciprocated to positively withdraw the engaged, lowermost blank from the base of the flexing magazine. To this end, a suction pump comprising a cylinder 70, bolted at 71 to the machine frame 30, is provided. A piston 73 reciprocates within the cylinder and, through a fitting 74 and suitable piping 92, actuates the suckers 40. The piston 73 is driven by a connecting rod 75, pinned at 76 to the piston and having an eccentric collar portion engaging an eccentric 80 keyed on the shaft 60 and adapted to rotate therewith. Thus, on rotation of the shaft 60, the piston 73 is reciprocated within the cylinder 70.

Valve mechanism, the details of which are best shown in Fig. 9, controls the suction created in the suckers by the pump cylinder 70 and piston 73 just described. This valve mechanism comprises a valve casing 85 bolted at 86 to the machine frame 30 and provided with a vertical cylinder 87. Leading into the cylinder 87 is a port 88 which by suitable flexible conduit means, such as a hose, communicates with the suckers 40. The cylinder 87 also includes an intake port 91 opening to the atmosphere, and an exhaust port leading to piping 92. This piping 92, in turn, communicates with the fitting 74 and also with a one-way check valve 94 which permits passage 15 of air out of the system to the atmosphere.

A valve piston 95 is mounted for reciprocation within the cylinder 87 and is provided with a portion of reduced diameter as indicated at 96 to permit communication between the ports in the cylinder when properly registered therewith. A spring 98 holds the valve piston downwardly against the follower of a rock arm 100. The rock arm 100 is pivoted intermediate its ends at 102 to the frame 30 and at its other end carries a follower which is engaged by a cam 105 on the shaft 60, to control the vertical reciprocation of the suckers, as will be hereafter described.

A blank feed slide 110 is mounted in ways 112 on the machine frame 30, for reciprocating motion toward and from the flexing magazine, and acts to feed the blanks pulled down by the suckers 40 from the base of the flexing magazine into the flexing rolls. This slide includes a series of rib-like fingers 114 which are adjustably bolted at 115 in corresponding slots of the slide 110. At their forward ends, the fingers 114 are provided with abutments 117 adapted to engage the rear edge of the blank which has been removed from the flexing magazine by the suckers 40 and push the same into the flexing rolls.

To drive the feed slide 110 a cam 120 is keyed to the shaft 60 for rotation therewith, and is engaged by a follower in the form of a bell crank 125 pivoted at 127 to the machine frame 30. A link 129 connects the other end of the bell crank 125 to the slide 110 to reciprocate the latter as the shaft 60 is rotated by motor 52.

From the description thus far, it will be apparent that the suckers 40, the suction pump and the feed slide 110 are all adapted for timed movement with relation to each other. In the normal sequence of operations, the column 48 is first raised by the cam 62 and rock arm 63 to engage the two suckers 40 with the under face of the lowermost blank in the stack of blanks in the flexing magazine. The pump piston 73 will have been moved in the meantime to the right (Fig. 2) by the eccentric 80 and connecting rod 75, to establish a vacuum in the suction line 92. Consequently, upon upward movement of the valve piston 95, by cam 105 and rock arm 100 to permit communication between the port 88 and the pipe 92, the sheet will, by reason of the vacuum created in the suckers 40, be drawn tightly against the soft cups at the tops of said suckers. Then, as the column 48 is lowered by the cam 62 and rock arm 63, the suckers 40 will move downwardly and the flexible blank which is lowermost in the flexing magazine and which is engaged by said suckers will be pulled out of the magazine past the discs 38 and will rest upon the forward ends of the fingers 114.

The rear edge of the blank which has thus been withdrawn from the flexing magazine is then engaged by the abutments 117 on fingers

114, which fingers and abutments are then moved from the left to the right as viewed in Fig. 2 by cam 120, bell crank 125, link 129 and slide 110, to push the blank into the flexing rolls. In the meantime, the suction created in the suckers 40 will have been released by movement of the valve piston 85 by cam 105, rock arm 100 and spring 88, to place the ports 80 and 81 in communication and the close off communication between port 90 and pipe 92. On the return stroke of the piston 73 effected by eccentric 80 and connecting rod 15, any air pressure built up in cylinder 70 is discharged to the atmosphere through the fitting 74 and check valve 94.

The flexing rolls (Fig. 5) comprise two 15 polished steel rolls 135 and 136, each of which is rotatably mounted in suitable bearings and which extend transversely of the direction of travel of the blanks from the flexing magazine. The lowermost roll 136 is carried in fixed bearings, while the upper roll 135 is carried in bearings mounted for vertical sliding movement toward and from the fixed lower roll bearings. The bearings for the rolls 135 and 136 are of such size that upon movement of the rolls toward each other the bearings will contact before the rolls contact, thus keeping the rolls separated from each other at a distance of at least a few thousandths of an inch. In practice this distance is approximately .006 inch.

To normally urge the two rolls together, a pair of compression springs 138 are provided, which springs at one end bear against the top of the upper roll bearings and at their other ends, are restrained by hollow bolts 139 threadingly received in the cross-member 140 at the top of the flexing device.

The lower flexing roll is positively driven by a sprocket pinion 142 at its left-hand end, Fig. 4. This pinion is engaged by chain 144 which in turn is driven from a sprocket 145 keyed to the shaft 60 for rotation therewith. The upper roll 135 is positively driven from the lower roll 136 by a gear drive 146 comprising a pinion on each roll, as shown at the right-hand side of Fig. 4.

A deflector blade 147 and a stripping and a leveling blade 148 are each adjustably bolted to sleeves 137 and 137' respectively, which sleeves loosely encircle the rolls 135 and 136 respectively. The position of the blade 147 controls the amount of flexing imparted to the blanks, and the blade 148 acts after the blank leaves the rolls 135 and 136 to control the amount to which the blank is again straightened. As a blank is fed to the rolls 135 and 136 from the left, Fig. 5, it is deflected down against the lower roll 136 by the deflector blade 147 and then passes upwardly between the bite of the two rolls 135 and 136. As it passes on through the rolls, it is stripped from the roll 136 and is leveled by the blade 148 and is then directed into the body maker magazine 10 adjacent the body maker proper. As the blank passes through the blades 147 and 148 and rolls 135 and 136, it is bent sharply to thereby break its grain and remove the resiliency thereof. The blanks are discharged from the flexing rolls 135 and 136 at a speed high enough to enable their momentum to carry them into the adjacent body maker magazine 10.

Each of the blades 147 and 148 is rotatably adjustable with respect to its cooperating roll 135 and 136 respectively by partially rotating the respective supporting sleeves 137 and 137' 75

about the axis of said cooperating roll. The upper blade 147 and its supporting sleeve 137 nest in a partial cylindrical recess in the top cross-member 140. The sleeve 137 is held in the recess by two bolts 150, which threadingly engage the sleeve and are suspended from a washer 152 with a curved outer face corresponding to the curve of the recess in the cross member 140 which receives said sleeve. Thus, as the bolts 150 are loosened and shifted along the direction of travel of a blank, there will be a corresponding repositioning of the blade 147 by reason of the movement of the supporting sleeve 137 thereof. After the desired position has been attained, the bolts 150 are again tightened and the blade is thus maintained in its adjusted position.

The blade 148 and its lower supporting sleeve 137' are carried in a partially cylindrical recess of the machine frame 30. Two pairs of bolts 154 pass through the top cross member 140 and have their lower ends bearing against corresponding faces 155 of the lower sleeve 137'. Thus, as the bolts 154 on one side of the axis of the roll 136 are loosened, and those on the other side of said axis are tightened, there will be a corresponding shifting of the lower sleeve 137' and the blade 148 supported thereby. It is thus possible to control the degree of flexing of a blank and the subsequent straightening effect exerted thereon, by positioning the supporting sleeves 137 and 137' and the blades 147 and 148 carried thereby.

The height of the stack of blanks in the body maker magazine 110 acts to control related mechanism to govern the feeding of blanks from the flexing device to the body maker magazine 10, and this mechanism is best shown in Figs. 1 and 3. As there shown, a flat, substantially rectangular shoe 160, having an upwardly inclined inner end 161, rests on top of the stack of flexed blanks in the body maker magazine 10, the construction being such as to allow blanks to freely move thereunder in passing from the flexing rolls into position in the body maker magazine 10. The shoe 160 is pivotally mounted at 162 on a rock arm 163, which in turn is keyed to a rotatably mounted shaft 164 journaled in end brackets 164' mounted at opposite ends of the top cross member 140. A second rock arm 165 is secured to the end of the shaft 164 and may be locked thereto to move as an integral part of the said shaft by means of a set screw 167.

A mechanically operated electric limit switch 170 is mounted beneath the free end of the rock arm 165 and is provided with an operating plunger 170' adapted to be engaged by the lower end of an adjustable bolt 169 mounted in the free end of the rock arm 165 when the shoe 160 has been raised to a predetermined height by the presence of sufficient blanks in the body maker magazine 10.

When the limit switch 170 is closed, it operates a solenoid 172 (Fig. 2) connected with a source of electric power 174, to shift a valve 175 interposed in the pipe 92. The valve 175 is normally retained in open position by a suitable spring (not shown) to provide an open conduit from the fitting 74, through pipe 92, to the valve casing 85. This solenoid 172 closes the valve 175 against the spring when the limit switch 170 is closed and cuts off communication between the cylinder 70 and the suckers 40 and at the same time opens a port 175' which connects the cylinder 70 with the atmosphere. This insures that

no load will be placed on the piston 73 as it is reciprocated within the cylinder 70.

When sufficient blanks have been fed from the body maker magazine 10 into the body maker to allow the shoe 160 to drop far enough to release the limit switch 170, the solenoid 172 is no longer energized by the current from the source 174. At this time, the valve 175 is shifted by the aforesaid spring to return said valve to its initial open position, to close the port 178 to atmosphere and to again directly connect the piping 92 with the cylinder 70. In this position, the suckers 40 no longer idly reciprocate but again act on each stroke of column 48 to feed the lowermost blank from the flexing magazine to a position where said blank is engaged by the fingers 114 and abutments 111 and is fed to the flexing rolls 135 and 136. The flexing rolls, due to their grip on the blank and the speed of rotation of said rolls discharge the blank at a rate high enough to carry it into the body maker magazine 10.

It will be apparent that during operation blanks are removed from the flexing magazine faster than they are removed from the body maker magazine, thus insuring that an excess will be built up in the latter sufficient to periodically cut off the action of the suckers 40.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a machine for forming containers from flat sheets, a frame, a magazine carried thereby from which blanks may be removed at the bottom, a flexing device mounted adjacent said magazine to receive blanks discharged therefrom, suckers reciprocably mounted in said frame beneath said magazine, a suction pump carried by said frame and operatively connected to said suckers, a valve in said connection adapted to open to atmosphere temporarily to terminate the pump suction action, a solenoid to actuate said valve, means to reciprocate said suckers to engage the lowermost sheet in said magazine and remove the same therefrom, a slide adapted to engage said removed blank and feed the same into said flexing rolls, a second magazine, power means to drive said flexing rolls at a speed sufficient to discharge blanks therefrom with sufficient momentum to carry them into said second magazine, and means responsive to the height of blanks in said second magazine to actuate said solenoid to open said valve and connect said pump to atmosphere upon the attaining of a predetermined blank level in said second magazine.

2. In a machine for forming containers from flat sheets, a frame, a magazine carried thereby from which blanks may be removed at the bottom, a flexing roll mounted a predetermined distance from said first roll, a second flexing roll resiliently urged against said first roll, suckers reciprocably mounted in said frame beneath said magazine, a pump carried by said frame and operatively connected to said suckers, a valve in said connection adapted to open to atmosphere temporarily to terminate the pump suction action, a solenoid to actuate said valve, means to reciprocate said suckers to engage the lowermost sheet in said magazine and remove the same

therefrom, a slide adapted to engage said removed blank and feed the same into said flexing rolls, a second magazine, power means to drive said flexing rolls at a speed sufficient to discharge them therefrom with sufficient momentum to carry them into said second magazine, a movable shoe engaging the blank in said second magazine to actuate said solenoid to open said valve and connect said pump to atmosphere upon the attaining of a predetermined blank level in said second magazine.

3. In apparatus of the class described adapted to form flat blanks into container bodies, a first magazine adapted to receive and contain a stack of blanks, a second magazine spaced from said first magazine and adapted to receive and contain a stack of blanks, flexing means interposed between said magazines to break the grain of a blank, means for feeding blanks from said first magazine through said flexing means and into said second magazine, means for feeding blanks from said second magazine at a speed lower than that at which the blanks are fed from the first magazine, and means to render ineffective the feeding means for the first magazine when the stack of blanks in said second magazine reaches a predetermined level.

4. In apparatus of the class described adapted to form flat blanks into container bodies, a first magazine adapted to receive and contain a stack of blanks, a second magazine spaced from said first magazine and adapted to receive and contain a stack of blanks, flexing means interposed between said magazines to break the grain of a blank, means for feeding blanks from said first magazine through said flexing means and into said second magazine, means for feeding blanks from said second magazine at a speed lower than that at which the blanks are fed from the first magazine, means adapted to interrupt the feeding of blanks from said first magazine through said flexing means and into said second magazine, and means controlled by the level of the stack of blanks in said second magazine for actuating said means for interrupting the feeding of blanks from said first magazine when the stack of blanks in said second magazine reaches a predetermined level.

5. In apparatus of the class described adapted to form flat blanks into container bodies, a first magazine adapted to receive and contain a stack of blanks; a second magazine spaced from said first magazine and adapted to receive and contain a stack of blanks; flexing means interposed between said magazines to break the grain of a blank; means for feeding blanks from the first magazine through said flexing means and into said second magazine; means for feeding blanks from said second magazine; the feeding means for the first magazine operating at a greater rate of speed than the feeding means for the second magazine whereby continued operation of the feeding means for the first magazine would result in an excess of blanks in the stack of blanks in said second magazine; and means to render ineffective the feeding means for the first magazine when the stack of blanks in said second magazine reaches a predetermined level.

6. In a can body making machine, a first magazine for a stack of blanks from which the blanks may be withdrawn downwardly, suckers beneath said magazine movable into engagement with the lowermost blank in said magazine, means to create a suction in said suckers sufficient to hold the lowermost blank thereon for removal from

the magazine as said suckers are lowered, means to lower said suckers, a pair of flexing rolls adjacent said first magazine, a slide to engage the blank removed from said magazine by said suckers and to feed the same into said flexing rolls, a second magazine adjacent said flexing rolls to receive the flexed blanks from said rolls, a movable shoe engaging the top of the stack of blanks in said second magazine, and means responsive to the position of said shoe to control the feeding of blanks from said first magazine to said flexing rolls.

7. In a can body making machine, a first magazine for a stack of blanks from which the blanks may be withdrawn downwardly, suckers beneath said magazine movable into engagement with the lowermost blank in said magazine, means to cre-

5 ate a suction in said suckers sufficient to hold the lowermost blank thereon for removal from the magazine as said suckers are lowered, means to lower said suckers, a pair of flexing rolls adjacent said first magazine, a slide to engage the blank removed from said magazine by said suckers and to feed the same into said flexing rolls, a second magazine adjacent said flexing rolls to receive the flexed blanks from said rolls, a movable shoe engaging the top of the stack of blanks in said second magazine, and means responsive to the position of the shoe to control the suction in said suckers and to thereby govern the feeding of blanks from said first magazine to said 10 15 flexing rolls.

FRANK KRUEGER.
